UNITED STATES PATENT OFFICE.

CHARLES R. MARTIN, OF MILWAUKEE, WISCONSIN, ASSIGNOR TO ALLIS-CHALMERS MANUFACTURING COMPANY, OF MILWAUKEE, WISCONSIN, A CORPORATION OF DELAWARE.

CENTRIFUGAL SWITCH.

Application filed April 17, 1922. Serial No. 553,628.

This invention relates to centrifugal switches. 55

One of the objects of the invention is the provision of a centrifugal switch mechanism including a plurality of snap switches. 5 A further object is the provision of such a mechanism in which the snap switches are operable at different speeds. Still another object is the provision of such a mechanism 10 in which it is possible to adjustably predetermine the speed at which the switches will operate.

Other objects will appear hereinafter as the description of the invention proceeds.

15 The novel features of the invention will appear from this specification and the accompanying drawings forming a part thereof and all these novel features are intended to be pointed out in the claims.

20 In the drawings:

Fig. 1 is a front elevation of a centrifugal switch embodying the features of the invention, the speed responsive means and its relation to the switch operating means being 25 shown but the switching mechanism being omitted for the sake of clearness.

Fig. 2 is a fragmentary detail view taken in the plane of the line II—II looking in the direction of the arrows.

30 Fig. 3 is a front elevation of a snap switch mechanism of conventional form the operating mechanism of which has been somewhat modified to adapt it for use with the present invention.

35 The centrifugal switch comprises a suitable rotatable member 1 provided with an axially extending flange 2, forming with the member 1 a cylindrical box which may be provided with a lid if desired. Disposed 40 between diametrically opposite points of the flange 2 is a rod 3, which may, if desired, be threaded at one end and screwed into flange 2 or fastened thereto in any other suitable manner. The rod 3 carries two centrifugally responsive members 4, 5; and it is of course understood that rod 3 is spaced from member 1 a distance such that members 4, 5 may slide freely on the rod 3. A tension spring 6 is provided surrounding rod 3 and flanges on members 4, 5, respectively. The ends of spring 6 are fastened in any suitable manner to members 4, 5 so that these members are biased toward each other.

A bell crank 7 is pivotally mounted on

screw 8 so as to be movable in the plane 55 of rotation. One arm of the bell crank is provided with a slot 9 cooperable with a screw 10 passing into the member 4. The screw 10 is freely slideable in slot 9.

Another bell crank 11 is pivotally mounted 60 on a screw 14 for movement in the plane of rotation and one end of this bell crank is provided with a slot 12 cooperable with a screw 13 passing into member 5. The screw 13 is freely movable in the slot 12. 65

The other arms of the bell cranks 11, 7 70 carry plates 15, 16, respectively. Plate 15 is pivotally mounted on a screw 17 while plate 16 is pivotally mounted on a screw 18 which latter also serves to pivotally mount an 75 equalizing rod 19 extending between the bell cranks 7, 11 and pivotally related to bell crank 11 by a screw 20. The plates 15, 16 may be made angularly adjustable with respect to bell cranks 11, 7 respectively, by 80 providing said plates with slots 27, 28 through which screws 29, 30 are adapted to pass into bell cranks 11, 7 respectively. The plates 15, 16 carry projections 21, 22 respectively.

85 A switch operating means 23 a top view of which may be had in Fig. 2 is provided with a slot 24. The switch operating means 23 is here shown as so disposed that if the projection 21 is rotated a sufficient amount in a counter-clockwise direction said projection will enter the hole 24 and upon further movement will move the operating member 23 to effectively actuate the switch connected therewith. A suitable form of 90 switch is shown in Fig. 3 in order to complete the illustration. The snap switch mechanism here illustrated is of conventional form and it is to be understood that any other suitable form may be utilized. In 95 view of this further description of this snap mechanism is deemed unnecessary.

Another switch operating member 25 is here shown disposed with respect to the projection 22 in such manner that when the centrifugal switch is at rest the projection 22 is disposed in a transverse hole 26 in member 25. A snap switch mechanism similar to that illustrated in Fig. 3 may be connected to the operating member 25. 100 105

The operation of the centrifugal switch is as follows:

Assuming the parts to be at rest, as shown

in Fig. 1, and the member 1 to be then set in rotation and the speed thereof gradually increased. As the speed increases the members 4, 5 will move radially outward, in opposite directions. Considering member 4, as this moves outward, screw 10 will rotate bell crank 7 in a counter-clockwise direction and the projection 22 will move the switch operating member 25 to the right, as viewed in Fig. 1. When the latter motion has proceeded a predetermined amount, the operating member 25 will have reached the dead-center position of the snap mechanism and when this center is passed the snap switch will be operated. The contacts of the switch operated by member 25 may be arranged, for example, so that a circuit is closed thereby when the parts are at rest and this circuit is opened when the switch is operated as hereinbefore described.

As the outward movement of members 4, 5 proceeds still further with an increase in speed, the projection 21, having been moved in a counter-clockwise direction by a bell crank 11, will enter the hole 24 in switch operating member 23 and, upon further movement, will operate the snap switch mechanism connected with member 23 in a manner already described in connection with member 25. The switch connected with member 23 may have its contacts so arranged that when operated in the manner hereinbefore described the circuit controlled thereby will be closed.

It is of course to be understood that current may be led to the switches connected with members 23, 25 in any suitable manner as by slip rings, not shown.

One of the uses to which the disclosed centrifugal switch may be put is in the control of valves for prime movers, the speed of the prime mover being varied by the setting of the valve. The switch operated by member 25 may, for example, be connected to a motor which will operate to open a valve of the prime mover. As the speed rises the switch 25 will be opened and further opening of the valve will be stopped. If the speed rises a predetermined additional amount the switch 23 will operate to close the circuit of the motor to cause the same to operate in a reverse direction to close the valve of the prime mover.

It should be understood that it is not desired to limit the invention to the exact details of construction shown and described; for various modifications may occur to persons skilled in the art.

It is claimed and desired to secure by Letters Patent:

1. In combination, two switches, means associated with each of said switches to cause each switch to operate with a snap action, a rotatable member, and means including a common actuator for said switches re-

sponsive to the speed of said member whereby as the speed rises one of said switches will be operated and as the speed rises still further, the other of said switches will be operated.

70

2. In combination, two switches, means associated with each of said switches to cause each switch to operate with a snap action, a rotatable member, and means including a common actuator for said switches responsive to the speed of said member whereby as the speed rises one of said switches will be opened and as the speed rises still further the other of said switches will be closed.

80

3. In combination, a rotatable member, at least two snap switches mounted on said member, and means including a common actuator for said switches responsive to the speed of said member whereby as the speed rises one of said switches will be operated and as the speed rises still further another of said switches will be operated.

85

4. A speed responsive switch comprising, a rotatable support, means movable in the plane of rotation and responsive to the speed of said support, a switch, means associated with said switch to cause said switch to operate with a snap action, said last named means being operatively related to said speed responsive means and having an operating member movable in a plane substantially at right angles to said speed responsive means.

90

5. A speed responsive switch comprising, a rotatable support, two snap switches with operating means mounted on said support, means responsive to the speed of and mounted on said support in operative engagement with one of said snap switches when said support is at rest and operatively engageable with the other of said switches at a predetermined speed of said support.

100

6. In combination, at least two switches, means associated with each of said switches to cause each switch to operate with a snap action, a rotatable member, and means including a common actuator for said switches responsive to the speed of said member whereby as the speed rises one of said switches will be operated and as the speed rises still further another of said switches will be operated, and means for adjustably predetermining the speed at which second named switch will be operated.

110

7. In combination, at least two switches, means associated with each of said switches to cause each switch to operate with a snap action, a rotatable member, and means including a common actuator for said switches responsive to the speed of said member whereby as the speed rises one of said switches will be operated and as the speed rises still further another of said switches will be operated, and means for adjustably predetermining the speed at which second named switch will be operated.

115

120

125

130

predetermining the relative speeds at which said switches will be operated.

8. In combination, a rotatable member, at least two switches mounted on said member, and means including a common actuator for said switches responsive to the speed of said member whereby as the speed rises one of said switches will be operated and as the speed rises still further another of said switches will be operated.

9. A speed responsive switch comprising, a rotatable support, at least two switches

with operating means mounted on said support, means including a common actuator for said switches responsive to the speed of and mounted on said support in operative engagement with one of said switches when said support is at rest and operatively engageable with another of said switches at a predetermined speed of said support. 15

In testimony whereof, the signature of the inventor is affixed hereto.
